UNITED STATES PATENT OFFICE.

EMILE COSTE, OF NEW YORK, N. Y., ASSIGNOR TO TITUS BLATTER & COMPANY, OF NEW YORK, N. Y., A CORPORATION OF NEW YORK.

DESIGN FOR TEXTILE FABRIC.

51,877.

Specification for Design.

Patented Mar. 19, 1918.

Application filed February 4, 1918. Serial No. 215,367. Term of patent 7 years.

To all whom it may concern:

Be it known that I, EMILE COSTE, a citizen of the Republic of France, residing at New York, in the county of New York and State of New York, have invented a new and original Design for an Article of Manufacture, of which the following is a specification, reference being had to the accompanying drawing, forming part thereof in which—

The figure is a plan view of a piece of textile fabric illustrating my new design.

It is to be understood, however, that my new and ornamental design is applicable not alone to fabrics, but is intended, and is equally well suited for the ornamentation of carpets, wall paper, and similar articles of manufacture having surface ornamentation, without in the least departing from my invention.

I claim as of my invention:

The ornamental design for an article of manufacture substantially as shown.

In testimony whereof I subscribe my signature in the presence of two witnesses.

EMILE COSTE.
